CARD SUPPORT

Roger Connor and Donald A. Nevin, Athens, Ohio,
assignors to The McBee Company, Athens,
Ohio, a corporation of Ohio

Application September 13, 1940, Serial No. 356,632

2 Claims. (Cl. 129—16.1)

Our invention relates to the manual sorting of cards so as to bring them into numerical sequence or to select a certain number of cards of a particular classification. Sorting of this kind is described in Patent No. 1,544,172 dated June 30, 1925 issued to Alfred Perkins. This application is a continuation in part of application Serial Number 321,826 filed March 2, 1940.

In this patent the cards are punched with a plurality of perforations adjacent their edge. The cards are then classified by notching or slotting the cards by cutting away the material between a perforation and the edge of the card, thus forming a pattern of notches relating to a single classification.

The cards thus notched or slotted can then be sorted by means of a needle or sorting device into numerical or other sequence.

In sorting the cards it is customary to grasp a number of cards of convenient size to hold in the hand, even the edges on a table or other convenient flat surface and then pass the sorting needle through the desired perforations or notches. If the cards get out of alignment it is difficult to pass the needle through the desired 25 perforations.

Our invention has for its principal object to provide a card support or holder which will have walls against which the cards may be stacked to even their edges and then hold them in correct 30 alignment.

A further object is to provide a card support or holder with a master plate or template one or more edges of which are notched or slotted to register with the perforations adjacent the 35 edge or edges of the cards.

Or means of accomplishing the foregoing objects may be more readily understood by having reference to the accompanying drawings, which are hereunto annexed and are a part of this specification in which:

Fig. 1 is an isometric perspective view showing our improved support as used in sorting a pack of cards;

Fig. 2 is a vertical sectional view of our improvement;

Fig. 3 is a side elevation showing the manner of using the master plate;

Fig. 4 is a modified form of construction showing the master plate in position;

Fig. 5 is a modified form of the construction shown in Fig. 4 with the master plate omitted;

Fig. 6 shows a modified form;

Fig. 7 is a detail view of said form;

Fig. 8 is a sectional detail view; and

Fig. 9 is a fragmentary detail view of the sliding bottom.

Similar reference numerals refer to similar parts throughout the entire specification.

5 As shown in the drawings our improved card support or holder comprises a four sided base preferably formed with a top 1, and four depending side walls 2. Angle irons 3, and 4, are welded or otherwise secured to two of the side walls. Feet 5 are fastened to the angle irons 2 and 3, adjacent the corners of the base. These feet should be made of rubber in order not to scratch a desk top or table on which the sorting is taking place.

15 Attached to the top 1 of the base by spot welding or in any other desired manner is a plate formed by a horizontal portion 6, and an upright or vertical portion 7. This plate furnishes a stop to limit the movement of the stack or cards from left to right when they are placed on the card support or holder, for the purpose of evening the edges and thus alining the perforations punched in the cards.

A front plate 8, is attached to one of the downwardly depending walls 2, of the card support by spot welding or in any other desired manner. This plate 8, should be spaced from the card support. As illustrated, this is accomplished by means of a strip of metal 9, which preferably extends inwardly about $\frac{1}{3}$ the height of the side wall 2, leaving a space 10, between the plate 8, and the wall 2. The purpose of this space is to allow the mounting of the master plate 11, in the space 10.

20 The master plate is formed with a series of notches in the edge along one side 12, and also along the edge of one of its ends 13. The other side 14, and the other end 15, are each provided with a slot 16, and 17, respectively. In some cases it may be found desirable to use two of these plates as shown in Fig. 6.

In Fig. 4 we have shown a modified form of holder in which the base is omitted to permit the stack of cards to rest on the desk or table top. In this form the holder consists of two connected walls 18 and 19. On the front wall 18 is cast or formed a shoulder 20, in which a slot 21 may be milled. In this form the master plate 11, should be formed with an offset portion 22, in order to present a flush surface to the stack of cards. Fig. 5 shows another form in which the walls 18' and 19' are connected by a hinge 23. This may be found convenient as the walls may be folded into a straight piece more easily stored.

It has been found in practice that it is sometimes desirable to use the modified form shown in Figs. 6 to 9 inclusive. In this form we provide a sliding bottom plate 24, the upper surface 26, of which is a plane surface. Attached to the under side 28 of this bottom plate is a corrugated piece of metal 30, clearly seen in Fig. 9, having a number of ridges 32, and grooves 34. This may be spot welded to the bottom or attached in any other suitable or convenient manner.

The sides 36 of the card support are each formed with an overhanging shoulder 38, which allow the bottom plate 24 to fit flush when in the up position. When the bottom plate 24 is in place beneath the cards, it will be in the up position shown in Fig. 8 in full lines. Further movement will cause the ridges 32 of the corrugated metal piece 30 to drop into grooves 40, formed in a corresponding piece of metal 42, fastened to the bottom of the card support.

This form of our invention is used as follows: When the stack of cards is placed in the support, with the sliding bottom 24, in the up position where it is resting on the two plates 30 and 42, by pushing the bottom 24 in, it will drop when the ridges 32 register with the grooves 40, and the drop will cause the selected cards to fall. It may also be used with a card having certain aligned perforations connected by slots. In such a case, the cards will drop just the length of the two-hole slot and a sorting needle can be inserted to remove from the top, such cards as have not fallen.

When the operator is ready to begin the sorting operation a master plate 11, which must correspond in size to the cards which are to be sorted, is inserted in the space 10, with one of the notched edges 12, or 13 uppermost according to which the edges of the cards are to be used in sorting, the slot 16 or 17 according to the arrangement of the cards being at the left.

A stack of cards is grasped in the left hand

and retained in that position while placing them upon the card support or holder. They are then moved toward the right until all the cards are stopped by the side plate 7, the operator's thumb passing into the slot 16 or 17, which is provided for that purpose. The operator may then rest the needle in the notch of the master plate which is in register with the desired perforation and continue as taught by the said Perkins Patent No. 1,544,172. Substantially the same steps are taken with the modified forms, Figs. 4 and 5, except that instead of placing the stack of cards on the top 1 of the base, the operator places them on the table and moves them until they abut the wall 19 or 19', and the offset portion 22, of the master plate 11, inserted in the slot 21. Other than this the procedure is the same and the sort is carried out in the same manner.

Having described our invention what we regard as new and desire to secure by Letters Patent is:

1. In a device for sorting cards, a flat base, upwardly extending side walls on only two adjoining sides of said base, one of said walls being spaced from the base and a single master plate removably mounted in said space, one or more edges of which plate are provided with notches which are adapted to register with perforations in said cards, there being thumb slots formed in the unnotched edges of said plate.

2. In a device for sorting cards, a flat base, upwardly extending side walls on only two adjoining sides of said base, one of said walls being spaced from the base and a single rectangular master plate removably mounted in said space, two adjacent edges of which plate are provided with notches which are adapted to register with perforations in said cards, there being thumb slots formed in the two adjacent unnotched edges of said plate.

ROGER CONNOR.
DONALD A. NEVIN.
